BRACKET FOR USE WITH LIFESAVING EQUIPMENT

Theodore Ziaylek, Jr., P.O. Box 292,
Yardley, Pa. 19068

Filed Mar. 11, 1969, Ser. No. 16,186

Term of patent 14 years

Int. Cl. D8—08

U.S. Cl. D8—247

FIG. 1 is a perspective illustrating a bracket for use with lifesaving equipment embodying my new design;

FIG. 2 is a top plan view of the equipment illustrated in FIG. 1;

FIG. 3 is a side elevation of the equipment illustrated in FIG. 1; and,

FIG. 4 is a rear view of the equipment illustrated in FIG. 1.

The broken lines are for illustrative purposes only.

I claim:

The ornamental design for a bracket for use with life-saving equipment, as shown and described.
